COMBINATION PADLOCK

George P. Junkunc, Palos Heights, Ill., assignor to Junkunc Brothers, Chicago, Ill., a partnership

Application June 3, 1955, Serial No. 36,347

Term of patent 14 years

(Cl. D50—8)

Fig. 1

Fig. 2

Fig. 3

The rear of the padlock is plain.

I claim:

The ornamental design for a combination padlock, as shown and described.
